UNITED STATES PATENT OFFICE.

JAMES CALLAGHAN, OF MONTREAL, QUEBEC, CANADA.

CIGARETTE-TIPPING MACHINE.

1,234,284.

Specification of Letters Patent. Patented July 24, 1917.

Application filed April 8, 1913. Serial No. 759,685.

To all whom it may concern:

Be it known that I, JAMES CALLAGHAN, a subject of the King of Great Britain, residing at the city of Montreal, in the Province 5 of Quebec and Dominion of Canada, have invented new and useful Improvements in Cigarette-Tipping Machines, of which the following is a full, clear, and exact description.

10 This invention relates to improvements in cigarette tipping machines, and the object is to provide means for applying tips of cork or other material to cigarettes with great rapidity and perfection of operation.

15 The device comprises essentially an endless belt upon which the cigarettes are fed from a hopper to the tipping mechanism, a feeding and pasting device for the tipping material, and means for holding the cigarette 20 during the tipping operation. Cooperating with these elements are means for cutting the tipping material into suitable lengths, means for folding the lengths partially around a cigarette, and means for 25 pressing the material against the cigarette to complete the tipping operation.

In the drawings which illustrate the invention:—

Figure 1 is a front elevation of the machine.

Fig. 2 is a plan view of same.

Fig. 3 is a right hand end elevation on an enlarged scale.

Fig. 4 is a rear elevation of the machine.

35 Fig. 5 is a left hand end elevation of the tipping mechanism on the same scale as Fig. 3.

Fig. 6 is an enlarged view of a fragment 40 of the tipping wheel showing the first step of the tipping operation.

Fig. 7 is a view similar to Fig. 6 showing the second step of the tipping operation.

Fig. 8 is a view similar to Figs. 6 and 7, showing the third step.

45 Fig. 9 is a right hand end elevation of the tipping mechanism on the same scale as Figs. 3 and 5.

Referring more particularly to the drawings, 11 designates the bed of the machine 50 upon which all the parts are mounted. At the ends of this bed are transversely disposed shafts 12 upon which are rigidly mounted drums 13 supporting the cigarette carrying belt 14. At the right hand end 55 of the machine, the shaft 12 also carries in front of the belt a tipping wheel 15 and at

the rear of the belt a ratchet wheel 16. A power distributing shaft 17 is mounted at the front of the bed and is arranged longitudinally thereof. This shaft is connected 60 by miter gears 18 with a cross shaft 19, extending to the rear of the bed. This cross shaft 19 is provided at the rear of the carrying belt 14 with an eccentric 20, having a pawl 21 fixed thereto at one end and at the 65 other end engaging the ratchet wheel 16. By this means, the carrying belt 14 and tipping wheel 15 will be partially rotated through equal distances at regular intervals of time.

70 The cigarette carrying belt 14 consists of a plurality of short wide links 22 pivotally connected, and each provided on its upper surface with a cigarette holding groove 23. The width of the links 22 is approximately 75 equal to the length of a cigarette, so that the cigarettes will be supported throughout their entire length and held against any relative movement by the grooves in which they lie. The cigarettes are contained in a 80 hopper 24 mounted at the left hand end of the machine above the belt 14, and feed out through an opening 25 at the bottom of the hopper into the grooves of the belt. The outlet of the hopper may be provided with 85 a gate of any suitable form (not shown) for regulating the escape of the cigarettes.

89 The tipping wheel 15 is much narrower than the carrying belt 14, its width being approximately equal to the length of the 90 tip which is to be applied to the cigarettes. This wheel comprises a central web 26 having a thick flange or rim 27 overhanging toward the front of the machine. This rim is serrated or divided into teeth 28 somewhat similarly to a gear with, however, the difference that the flanks of the teeth are parallel, so that the spaces 29 between them are V-shaped. The top of each tooth is provided with a groove 30 corresponding with 95 the grooves 23 of the carrying belt 14, the teeth 28 being so spaced that these grooves will register with the grooves of the belt, so that cigarettes may be projected endwise from the grooves of the belt into the grooves 100 of the tipping wheel. Each tooth of the tipping wheel is hollowed out, as indicated at 31, the aperture extending from the inner periphery of the rim to within a short distance of the bottom of the groove. This 105 recess is brought into communication with the groove through a plurality of minute

or capillary apertures 32. At the point where the tipping operation is to be performed, a suction box 33 is provided pressing against the inner periphery of the rim 5 so as to be in communication simultaneously with a plurality of tooth recesses 31. As the joint between the suction box and tipping wheel rim is made as nearly fluid tight as possible, it will be seen that the only air 10 inlet is through the capillary apertures 32.

The tip pasting and feeding mechanism is all mounted on a vertical frame 34 secured to the bed a short distance in front of the carrying belt 14. The tipping material 15 which may be cork, gold or silver surfaced paper, or the like, is prepared in the form of a ribbon and wound on a spool 35 carried by the frame 34. The ribbon of tipping material designated 36 passes downwardly from the spool under a double flanged idler roll 37, and over a similar roll 38, above which is mounted a knurled pasting roll 39, the upper portion of which projects practically through the bottom of a paste reservoir 40 and carries the paste out 20 by means of its roughened surface. The tipping material after passing under the paste roll passes between a pair of knurled discharge rolls 41 and 42 into a trough 43, through which it slides onto the tipping wheel 15. The material is prevented from escaping from the trough, and is also pressed down onto the tipping wheel by a gravity actuated pivoted arm 44. This arm 25 also slightly retards the movement of the material, so that sufficient slackness is maintained to enable the material to be drawn down into the grooves of the wheel by the suction. The upper discharge roll 41 is 30 mounted at one end of a bell-crank lever 45, the pivotal end of which is connected to a tensioned spring 46 which operates to press the roll 41 downwardly against the roll 42. The paste roll 39 and lower discharge roll 45 42 are provided with small chain wheels 47 and 48 respectively, over which an endless chain 49 passes to a drive wheel 50 mounted on the cross shaft 19. It will be noted in 50 Fig. 1 that the wheel 48 of the discharge roll is slightly smaller than the wheels 47 and 50 which are of equal size, so that the discharge roll will turn a trifle faster than the paste roll, and thus keep the material in tension. The relative speeds of the various 55 parts of the machine are necessarily such that the tipping material is pasted at exactly the same speed that it is used. The slightly increased speed of the discharge rolls therefore co-operates with the presser arm 44 to maintain the slackness previously described.

A disk 51 is rigidly mounted on the rear end of the shaft 19 and is provided on its rear side with a cam track 52, arranged to 60 travel under a roller 53 carried on the free

extremity of an arm 54, the opposite extremity of which is secured to a short shaft 55 extending along the rear edge of the bed. The opposite end of this shaft 55 is provided with an arm 56 having the upper extremity thereof bifurcated to embrace a horizontal spindle 57 between two collars 58 formed thereof. This spindle is slidably mounted in a post 59 secured to the machine bed in the rear of the cigarette carrying 75 belt 14, and substantially in line with the right hand end shaft 12. A bracket 60 is secured to the top of this post and overhangs the carrying belt 14, in which position it carries a vertical guide 61 in which 80 a slide 62 is mounted. A short shaft 63 is journaled near the base of this bracket, and carries at opposite ends thereof arms 64 and 65. The arm 64 is provided at its free end with a roller 66 in engagement with a cam 85 track 67 formed in the front face of the disk 51. The second arm 65 is pivotally connected at its free end to the vertical slide 62, which carries at its lower end a presser plate 68 adapted to press the cigarettes firmly 90 down on the carrying belt and hold them against movement during the tipping operation. It will be noted springs 69 and 70 are provided to normally hold the spindle 57 and presser plate 68 out of engagement with the carrying belt 14. It will be noted that the cam track 52 is so arranged as to influence the arm 54 slightly before the cam track 67 influences the arm 64. This sequence of operation permits the spindle 57 100 to slide over the cigarette carrying belt and project a cigarette thereon into a groove 30 of the tipping wheel, and then return to its original position before the holding plate 68 descends and clamps the cigarette in this 105 projected position.

The tipping and tip material cutting mechanism are mounted on a horizontal slide 71 reciprocatable transversely of the bed in a guide 72, rigidly mounted on the bed. The power distributing shaft 18 passes 110 through this guide, and the slide 71 is suitably slotted, as indicated at 73, for the passage of the shaft and to permit of its reciprocation. Preferably on the left hand side 115 of the slide, a cam 74 is rigidly mounted on the shaft 17 and bears against a roller 75 mounted on the slide. Suitable springs 76 are provided to hold the roller and cam constantly in engagement.

A vertical slide 77 is mounted by means of guides 78 on the right hand side of the horizontal slide at the rear end thereof. This vertical slide is connected by means of a link 79 with one end of a lever 80 pivoted 125 intermediate its extremities to the horizontal slide 71, and having at its opposite end a roller 81 positioned to be brought into engagement with a cam 82 mounted on the shaft 17 when the horizontal slide 71 moves 130

rearwardly. A spring 77^a operates to hold the vertical slide normally in its lowered position, while a stop 83 limits the downward movement. Fixed to the slide is an arm 84 having the free end thereof bifurcated, as shown at 85. This bifurcated portion is so proportioned and positioned that when the slide is in its lowered position, the bifurcations will embrace the bottom of the uppermost tooth 28 of the tipping wheel 15, as indicated in Fig. 6. These bifurcations are each provided with a plurality of upwardly projecting pins 86 and 87, the pins 86 being on the left hand bifurcation and of such length that their upper extremities will lie flush with the top of the tooth 28, when the member carrying them is at the bottom of the tooth. The pins 87 are only half the height of the pins 86. The cam 82, which controls the upward movement of the vertical slide carrying the arm 84, is provided with a double lift, or more perfectly speaking, a two stage lift, as shown in Fig. 9, so that as the cam revolves it will first lift the arm 84 only half the height of the pins 86, that is, until the tops of the pins 87 are flush with the top of the tooth. On the further revolution of the cam, the second or higher stage of its lift engages the roller 81, and the arm 84 is lifted to its highest position with its top edge flush with the top of the embraced tooth.

The mechanism for cutting the tipping material into suitable lengths consists of a lower shear blade 88 fixed to the slide 71 and projecting rearwardly therefrom, its upper cutting edge being on a level with the top of the uppermost tooth 28 of the tipping wheel and positioned to enter the recess 29 at the left of the tooth when the slide 71 moves rearwardly. The upper shear blade 89 is rigidly secured to a vertically disposed spindle 90 slidably mounted in extensions 91 of the slide 71. This spindle and the blade 45 carried thereby are normally maintained in elevated position by a spring 92, held in compression between the top of the spindle and the upper extension 91 carrying the spindle. At the lower end of the spindle 50 are a pair of spaced collars 93 between which the bifurcated end 94 of a lever 95 embraces the spindle. This lever is pivoted at its rear end, and carries intermediate its ends a roll 96, adapted to be brought into engagement 55 with a cam 97 fixed on the shaft 17 when the horizontal slide moves to its forward position.

An arm 98 is pivoted at its upper extremity to the presser plate guide 61, and carries at its lower extremity a brush 99 positioned to engage the portion of the cigarette lying on the topmost tooth of the tipping wheel. A lever 100 is pivoted at its lower extremity to the machine bed, and at 65 its upper extremity is pivotally connected

by a link 101 with the arm 98 intermediate the ends thereof. This lever 100 carries near its lower end a roller 102, which is held in engagement with a cam 103 mounted on the shaft 17 by means of a spring 104. The normal position of the arm 98 is inclined with the brush at the left of the cutters 88 and 89. The cam actuated lever 100 oscillates the arm, so that the brush travels back and forth across the cigarette. The right hand 70 end of the distributing shaft 17 is equipped with a fixed pulley 105 and loose pulley 106 in the usual manner.

The operation of the various parts of the machine will be clearly understood from the foregoing description, taken in connection with the drawings, but in order to give a more perfect understanding of the invention, the coöperative action of the parts will be outlined. The cigarettes feed from the 80 hopper onto the carrying belt 14 and are carried thereby to a position behind the tipping mechanism. The tipping material is simultaneously pasted and fed pasted side uppermost to the tipping wheel at the point 90 where tipping takes place. When the tipping material is fed over the teeth of the tipping wheel, the suction draws the material down to conform with the curvature of the groove 30. The eccentric driven pawl and 95 ratchet mechanism moves the carrying belt and tipping wheel the space of one link, which brings the tip covered tooth of the tipping wheel and a cigarette on the belt in line with the bifurcated extremity of the 100 arm 84. This ratchet mechanism permits the belt and tipping wheel to remain at rest in this position sufficiently long for the performance of the tipping operation. As soon as the belt comes to rest with the cigarette 105 opposite the tipping mechanism, the plunger 57 presses the cigarette forwardly until it projects into the groove of the tipping wheel, and is thereby affixed to the pasted tipping material resting in the bottom of the 110 groove. The presser plate 68 then lowers and clamps the cigarette firmly against any movement during the tipping operation. Practically simultaneous with this movement, the slide 71 carrying the tipping and 115 cutting off mechanism moves rearwardly, so that the bifurcations 85 of the arm 84 project into the recesses 29 on each side of the uppermost tooth of the wheel. The cutting off device being mounted on the slide moves 120 forward simultaneously, and the upper cutter 89 descends and severs from the ribbon of tipping material a length sufficient to go around the cigarette. The cutter 89 preferably remains in its lowered position until 125 the tipping operation is completed, so as to be out of the way of the brush 99. The relation of the parts is now as shown in Fig. 6. The arm 84 now rises through one half of its travel, so that the upper portion 130

of the long pins 86 turns up the left hand end of the severed tip length, as clearly indicated in Fig. 7. The brush 99 operated by its cam actuated lever 100 moves to the right 5 and presses the tip down on the cigarette, where it is held by the adhesive. The brush now remains at the right of the cigarette, while the arm 84 completes its upward movement, so that the short pins 87 turn up the 10 right hand end of the tip length. The brush then returns to its original position pressing down the tip in passing, and thus completing the tipping. The slide 77 drops, the shear cutters separate, and the slide 71 15 moves forward and withdraws the tipping mechanism from engagement with the tipping wheel. Simultaneously with this movement, the presser plate 68 rises and liberates the cigarette. The ratchet now becomes effective to shift the carrying belt and tipping wheel, so that a fresh cigarette and length of tipping material are brought into register 20 with the tipping mechanism.

While this invention has been described 25 with reference to the specific form shown in the drawing, it is obvious that numerous changes may be made in the mechanism without departing from the spirit of the invention. For example, several simultaneously operated tipping mechanisms may be employed without making any further change in the machine than a slight alteration of dimensions and throw of the eccentric 30 to impart the proper feed to the carrying belt and tipping wheel.

Having thus described my invention, what 35 I claim is:—

1. In a cigarette tipping machine, a cigarette magazine, a carrying belt, a tipping wheel, a power shaft, a cross shaft driven thereby, means operated by the cross shaft for intermittently shifting the belt and tipping wheel, a double faced cam on the cross shaft, a lever operated by one face of said cam, a slideable spindle operated by said lever and arranged to project cigarettes from the carrying belt onto the tipping wheel between the shifts thereof, a post carrying said spindle, a bracket on said post, a guide 40 on the bracket above the carrying belt, a clamping member slidably mounted in said guide, a clamp operating lever pivotally mounted in the bracket and engaging the second face of said cam, and means coöperating with the tipping wheel to apply tips to the cigarettes held by the clamping means.

2. In a cigarette tipping machine, an intermittently moving grooved cigarette support, a continuously operating tip material pasting and feeding mechanism, a trough between the tip feeding mechanism and cigarette support, suction means arranged to hold pasted tip material in position on the cigarette support, a gravity actuated arm 45 coöperating with the trough arranged to

confine the slack of the fed tip material accumulated between shifts over the cigarette support, whereby the suction means will maintain the tipping material in conformity with the grooves of the cigarette support 70 during the shift thereof.

3. In a cigarette tipping machine, a cigarette support having a plurality of hollow teeth formed with their tops grooved, capillary ducts extending from the interior of the teeth to the bottom of said grooves, a tip pasting mechanism positioned to feed pasted tip material over the grooved tops of said teeth, a vacuum chamber positioned under the teeth and arranged to draw the tip material down into the grooves of the support by suction through the ducts, a continuous drive for the tip material pasting and feeding mechanism, an intermittent drive for the cigarette support, and a gravity actuated arm engaging the tip material arranged to regulate the feed thereof whereby the suction device will hold the material in the grooves during movement of the cigarette support.

4. In a cigarette tipping machine, a bed, a magazine, a tipping wheel, a belt arranged to carry cigarettes from the magazine to the wheel, a guide fixed to the bed, a slide mounted therein, cigarette tipping mechanism, a portion of said tipping mechanism being mounted on said slide, a shaft, and a cam on said shaft arranged to shift the tipping mechanism into and out of engagement with the tipping wheel.

5. In a cigarette tipping machine, a bed, a magazine, a toothed cigarette support, a belt arranged to convey cigarettes from the magazine to the support, means for feeding pasted tip material over the teeth of said support, means for projecting cigarettes from the belt onto the pasted material on the teeth of said support, a guide on the bed, a slide therein, tip severing shears mounted on said slide, tip end bending means mounted on said slide, shifting means for said slide arranged to position said shears, and tip bending means between the teeth of the support, means for operating said shears and tip bending means successively, and means for pressing the tip ends down on the cigarette in overlapping relation after the bending operation.

6. In a cigarette tipping machine, a bed, a magazine thereon, a toothed cigarette support, a belt arranged to carry cigarettes from the magazine to said support, means for intermittently shifting said belt and support, means for feeding pasted tip material over the teeth of said support, suction means for forming said tip material to receive the cigarette, means for projecting the cigarettes from the belt into engagement with the tipping material, a presser plate positioned to clamp the cigarette in

- projected position, a rigid guide on the bed, a slide therein, shears mounted on said slide, a bifurcated member on said slide adapted to embrace a tooth of the cigarette support, pins on the bifurcations of said member arranged to successively bend the ends of the tip around the cigarette, a power shaft, a cross shaft driven thereby, a cam on said cross shaft, levers engaging said cam arranged to operate the cigarette projector and presser plate successively between the shifts of the belt, a cam on the power shaft arranged to shift the slide and position the shears, a tip bending member in engagement between the teeth of the cigarette support, cams on said shaft, operating levers for said shears, a bifurcated member pivoted to the slide in position to engage and disengage said second cams on the movement of the slide, a brush positioned to press the tip ends down on the cigarette in overlapping position, an operating lever for said brush, and a cam on the power shaft actuating said lever. 40
- 5 7. In a cigarette tipping machine, a toothed cigarette support, means for feeding pasted tip material over the teeth of said support, means for projecting cigarettes endwise onto said tip material on the support teeth, tip length severing shears, a bifurcated arm adapted to embrace a tooth of the support at the root thereof, pins on one bifurcation of said arm extending to the tooth top, pins on the other bifurcation extending half way to the tooth top, means for positioning said shears and bifurcations between the support teeth, a brush, means operating said shears to sever a tip length, means for moving said bifurcated arm from the tooth root to the tooth top in two equal shifts whereby the tip ends will be turned into the path of the brush successively, and means operating the brush to press the tip ends against the cigarette as they are bent by the bifurcated member. 45
- 10 8. In a cigarette tipping machine, a toothed cigarette support, a bifurcated member adapted to embrace a tooth of said support, means for moving said arm into and out of engagement with the support, and a double lift cam arranged to move said bifurcated arms from the bottom to the top of the support tooth in two separate equal shifts during engagement between said member and the cigarette support. 50
- 15 9. In a cigarette tipping machine, an intermittently moving toothed cigarette support, a stationary guide, a horizontally movable slide therein movable toward and away from the cigarette support, a vertically movable arm mounted on said slide, bifurcations on said arm adapted to embrace a tooth of the support, a shaft, a slide shifting cam thereon arranged to bring said bifurcations into engagement with the cigarette support between the shifts thereof, a cam on said shaft having two lifts of different heights, a lever pivoted to the slide and to the bifurcated arm, and a roller on said lever positioned to engage the two lift 55 cam during engagement of the bifurcated arm with the cigarette support. 60
- 20 30 35 In witness whereof I have hereunto set my hand in the presence of two witnesses.
- JAMES CALLAGHAN.
